[57] ABSTRACT

A facial muscle exerciser is described comprising a disc insertable between the lips and teeth, said disc being integrally connected to a resilient member or to a rigid barrel containing such resilient member.

4 Claims, 3 Drawing Figures

PATENTED APR 23 1974

3,805,771

FACIAL MUSCLE EXERCISER

SUMMARY OF THE INVENTION

The structure disclosed, when properly manipulated, exerts intermittent forward pressure on the lips and for that purpose is inserted between the teeth and lips, causing the firming and restoring of the tone of the lip and other facial muscles. The structure comprises a disc insertable between teeth and lips, a resilient member connected integrally to the disc, via the intermediary of a short stem extending from the center of the disc. The resilient member may, by way of example, consist simply of an elastic rubber tubing attached to the short stem, which may or may not be provided with an auxiliary holding means at its free end. The resilient member may also comprise a resiliently mounted rigid tubing. The resilient member causes intermittent forward pressure to be exerted on the lips through the disc portion.

BACKGROUND OF THE INVENTION

The applicant calls attention to the following prior United States Patents which are representative of the lip exerciser art.

PATENTEE	U.S. PAT. NO.	ISSUE DATE
C. G. Purdy	1,953,088	Apr. 3, 1934
L. Barons	3,118,667	Jan. 21, 1964

Neither of the above listed patents discloses the simplified and resilient construction of applicant's invention.

DESCRIPTION OF THE DRAWINGS

FIG. 1 is a side view, partially in section, of the facial muscle exerciser, illustrating the position of its disc in the mouth behind the lips. The two oppositely directed arrows indicate the alternating forces to which the resilient member is subject;

FIG. 2 is a perspective view of a portion of the facial muscle exerciser of FIG. 1; and

FIG. 3 is a perspective view of a modified facial muscle exerciser.

DESCRIPTION OF THE PREFERRED EMBODIMENT

This invention relates to a facial muscle exerciser, which primarily is concerned with the strengthening and firming up of facial muscles such as zygomaticus, triangularis, labii superioris and inferioris, mentalis, orbicularis oris, caninus and others in order to restore their muscle tone and as a cosmetic aid to men and women — to delay or to minimize the formation of wrinkles of the lip area.

The invention is also intended for use in orthodontics by individuals who suffer from malocclusion, the improper closing or alignment of the teeth (which prevents normal mastication of foods) and is intended for use with other muscular facial problems, as well. The prevention, or improvement, of these conditions becomes especially important during the formative years of permanent teeth.

It is a primary object of this invention to replace or complement devices hitherto used in therapy of facial muscles by providing a safe, simple and efficient device for stimulation and strengthening of the facial muscles thus aiding in developing healthier and stronger muscles.

It is another major object of the invention to provide an exercising device for use in orthodontics, which exerts stimulation pressure, simultaneously on the upper and lower lips, thus strengthening the lip muscles thereby contributing to the minimization of the protraction of teeth, particularly in children.

With reference to the drawing, as illustrated in FIG. 1, the facial muscle exerciser 8, comprises a plastic disc 10, insertable manually for placement between the teeth and the upper and lower lips. The disc 10, preferably of circular shape, is provided with a short integral plastic stem 14, extending integrally from the center thereof, which is adapted to be rigidly connected to one end of a resilient member, for example, an elastic rubber tubing 12. One end of tubing 12 is affixed to the outer end of the stem 14 by a metal or plastic ring 15 of appropriate size. The disc 10 should preferably measure about 20-35 mm. and optimally about 25 mm. in diameter. The resilient member preferably has a normal unstretched length of about 60-100 mm, about 75 mm. being optimal. The other end of rubber tubing 12 serves as a manual holding point during the exercises.

FIGS. 1 and 2 both illustrate the use of the facial muscle exerciser, the disc portion 10 of which is manually inserted, as described, for exerting outward pressure on both upper and lower internal lip surface when the resilient member 12 is stretched, and relieving said pressure as the resilient member is relaxed.

FIG. 3 shows a second embodiment of the facial muscle exerciser and is designated by the numeral 20. The shape of the plastic disc 22 in this embodiment, is not circular and is adapted to more precisely conform to the contours of the lip area subjected to the exercise and may be further modified to meet individual requirements of the patient, depending on which facial muscles are to be firmed.

The resilient member of the modified form of exerciser 20 comprises a spring-loaded plunger 29 carried within a rigid barrel 26, said barrel being attached to a plastic stem 24 which, in turn, is affixed to the disc 22.

More specifically, the plastic stem 24 is integrally molded to the disc 22. One end of the rigid barrel 26, preferably made of plastic or metal, is affixed to stem 24. The other end of the barrel 26 has a plastic plug 18 fitted therein, said plastic plug 18 having an opening for movement of a spring-loaded plunger 29 therethrough.

Plunger 29 comprises a handle 30, a stem 28 affixed to the handle and an inner end 34 removably affixed to stem 28. The stem 28 of the plunger passes through the apertured plug 18. A spring 32 is held between inner end 34 of the plunger and the plug 18 of the barrel 26. The plunger 29 rides within said barrel from a position wherein the spring 32 is not compressed (as shown in FIG. 3) to a position wherein the spring is compressed — by moving the plunger to the right in FIG. 3. The spring 32 is then compressed between the inner end 34 of the plunger and the plug 18 of the barrel 26 causing pressure to be exerted by the disc 22 on the lip and other facial muscles. Upon relaxation of pressure on the plunger 29, the plunger moves to the left in FIG. 3 under the influence of spring 32 and no pressure is then exerted on the lip and facial muscles.

The user of the facial muscle exerciser 20 merely places the disc 22 between the lips and teeth and ini-

tially pulls forwardly (to the right in FIG. 3) on the handle 30 of the plunger 29, thus imparting a strong forward pressure of the disc 20 against the lips. This pressure as applied against the lips is found to have a beneficially firming effect on the lip and other facial muscles.

While the foregoing has illustrated and described what is now contemplated to be the best mode of carrying out the invention, the embodiments of the invention are, of course, subject to modification without departing from the spirit and scope of the invention. Therefore, it is not desired to restrict the invention to the particular form of construction illustrated and described, but to cover all modifications that may fall within the scope of the appended claims.

I claim:

1. A facial muscle exerciser, comprising:
a solid, noninflatable disc of sufficient thinness to be readily insertable between the teeth and lips;
a resilient member, one end of which is affixed to said disc, the reciprocal motions of said resilient member causing said disc to exert intermittent pressure against the lips.
2. The facial muscle exerciser of claim 1 wherein said resilient member consists of a rubber tube having one

end thereof affixed to said disc and the other end thereof free to move in reciprocal motion to cause said disc to exert intermittent pressure against the lips.

3. A facial muscle exerciser, comprising: a disc, insertable between teeth and lips;

a stem integrally connected to and extending from the center of said disc;
a barrel mounted onto the free end of said stem;
a resilient member accommodated with the barrel;
a plunger mounted for reciprocating movement within said barrel; and
a spring means fitted within said barrel and movable with the movement of said plunger from a compressed state to a decompressed state.

4. A facial muscle exerciser, comprising:
a disc insertable between the teeth and lips;
a resilient member, one end of which is affixed to said disc, the reciprocal motions of said resilient member causing said disc to exert intermittent pressure against the lips, said resilient member comprising a rigid barrel and a spring-loaded plunger riding within said barrel whereby the spring of said spring loader plunger may be compressed and decompressed.
